SHAFT OR TUBE PRESS

Ulysses A. Inman, Long Beach, Calif.

Application October 4, 1937, Serial No. 167,244

2 Claims. (Cl. 153—52)

This invention relates to a shaft or tube press particularly adaptable for the straightening of tubes or shafts of an automobile.

An object of my invention is to provide a simple, inexpensive and effective press of the character stated, including a means for holding the shaft or tube either downwardly, or upwardly, depending on the direction of the pressure which is applied to the tube, or shaft, in straightening the same.

Another object is to provide a novel press of the character stated in which the load is taken off the centering cones or centering pins, while the member held in the press is being straightened.

Other objects, advantages and features of invention may appear from the accompanying drawing, the subjoined detailed description, and the appended claims.

In the drawing—

Figure 1 is a side elevation of my press.

Figure 2 is an enlarged sectional view taken on lines 2—2 of Figure 1.

Figure 3 is a fragmentary transverse sectional view of one of the chucks, showing the centering cone mounted thereon.

Referring more particularly to the drawing, my press includes a bed 1, which is supported on legs 2, 3. The leg 2 extends above the bed 1, and an adjustable chuck 4 is mounted adjacent the upper end of this leg.

A tail block 5 is adjustably mounted on the bed 1 so that the press can accommodate a shaft or tube of different lengths. The tail block 5 carries a centering pin 6, and the shaft 7, which is being worked upon, is held between the chuck 4 and the pin 6. The bed 1 comprises a pair of spaced structural members 8, 9, which carries the holding members as well as the straightening jack, as will be further described.

A pair of holding members 10 are adjustably mounted on the bed 1 and since both of these holding members are alike, only one will be described in detail.

A post 11 is provided with a flange 12, which rests on the bed 1. A depending stem 13 extends between the structural members 8, 9, of the bed, and a clamping wedge or the like 14 is driven through the stem, and bears against the bottom of the bed, thereby holding the post securely in position.

By removing the wedge 14, the post 11 can be moved along the bed as desired. The upper portion of the post is threaded and receives a turnbuckle 15. A threaded bolt 16 screws into the upper end of the turnbuckle, and includes a head

17 which bears against the work, if the holding member is pushing upwardly. If the holding member is pulling downwardly, a yoke 18 encircles the shaft or tube 7, and this yoke is affixed to the head 17 by the pin 19.

A jack 20 rests on the bed 1 and is moved as desired in order to press against the work 7 to enable the operator to straighten certain parts of the work.

If a tube is to be worked upon, a cone 21 is fitted over the pin 6, and the outer end of the chuck, thus enabling the tube to be accurately centered in the press. The cones are machined to fit over the pins and can be removed when desired.

In operation, the work is set in the press and is aligned, either by means of the pins, or the cones, and thereafter, the holding members 10 are positioned on the press. By adjusting the turnbuckles 15, the work is either pulled downwardly, or pushed upwardly, and when the jack 20 is then operated, the load is not carried by the pins or the cones, but is entirely carried by the holding members.

Having described my invention, I claim:

1. A shaft or tube press comprising a bed, having a longitudinal slot therein, a pair of spaced centering means mounted above the bed, the work being adapted to be held between the centering means, a work engaging fixture comprising a stem extending through the slot in the bed, lock means on the stem whereby the fixture is held against longitudinal movement on the bed, a turnbuckle on the fixture whereby the fixture may be elongated and a yoke on the upper end of the fixture adapted and arranged to partly encircle and engage the top of the work, whereby the fixture may push upwardly or pull downwardly on the work.

2. A shaft or tube press comprising a bed, a pair of spaced structural members forming said bed, centering means mounted above the bed, the work being adapted to be held between the centering means, a pair of work engaging fixtures, each fixture including a stem, said stem extending between the structural members of the bed, lock means on the stem, whereby the fixture is held stationary on the bed, a turnbuckle on the fixture whereby the fixture may be elongated, a head on the upper end of the fixture engageable with the bottom of the work, a yoke on the fixture engageable with the top of the work whereby the fixture may push upwardly or pull downwardly on the work.

ULYSSES A. INMAN.
